John Thornton,
INVENTOR,

BY

W.C. Carnan

ATTORNEY

UNITED STATES PATENT OFFICE.

JOHN THORNTON, OF YOUNGSTOWN, OHIO.

FURNACE-DOOR FRAME.

1,407,708.

Specification of Letters Patent. Patented Feb. 28, 1922.

Application filed December 8, 1920. Serial No. 429,154.

To all whom it may concern:

Be it known that I, JOHN THORNTON, a citizen of the United States, residing at Youngstown, in the county of Mahoning and 5 State of Ohio, have invented certain new and useful Improvements in Furnace-Door Frames, of which the following is a specification.

This invention relates to open-hearth 10 furnace door-frames, and has for its object the protection of the furnace wall immediately adjoining the inner end of the charging port of the door-frame.

Figure 1 is a view in perspective, showing 15 the front, top and one end of the furnace door-frame; Figure 2 is a vertical longitudinal section on line 2—2 Figure 3; Figure 3 is a vertical transverse section on line 3—3 Figure 2; Figure 4 is a horizontal sectional view on line 4—4 Figure 2, looking 20 in the direction of the arrow; Figure 5 is a front view showing a modified construction, including a passageway through the frame for the purpose of making slight repairs 25 without removing the frame; Figure 6 is a vertical longitudinal section on line 6—6 Figure 7, and Figure 7 is a vertical transverse section on line 7—7 Figure 5.

In the ordinary construction of open 30 hearth furnaces, the door-frame is set up against the outer side of the furnace wall, the charging port through the door-frame registering flush with the opening in the wall, so that the opening in the wall may 35 be said to be, in effect at least, a continuation of the charging port,—no part of the frame being encased within the wall. This construction, of course, leaves the brick of the wall around the opening absolutely ex- 40 posed and unprotected, and subject to constant interference and disturbance by the charging apparatus, as it is forced through and beyond the inner end of the port proper, making necessary repairs and renewals of 45 this wall of frequent occurrence. Such repairs are unusually costly and expensive, by reason of the difficult accessibility to the place where they are to be made.

As indicated above, the object of my in- 50 vention is to provide this immediate portion of the furnace wall with protection against such interference and destruction by the charging apparatus.

As is well known to the trade, these door- 55 frames are of metal and of hollow forma-

tion, through which water is circulated for cooling purposes. In the drawings, projections or flanges 1—1, Figure 1, represent the door guides of the frame between which the door slides up and down, being held 60 in perpendicular position by its own weight.

The inlets or pipes 5 are such as are ordinarily used to maintain the water circulation through the frame for cooling purposes.

6 represents the port of the door-frame 65 through which the furnace is charged. Around the inner end of this port I provide a hollow guard flange or projection 7, preferably built integrally with the frame, as an abutment against which the brick-work or wall 8 of the furnace may be built, in order to keep it back, and away, from the wall or opening of the port, so that the charging apparatus may be forced through the port, and into the furnace, without the 75 possibility of coming into contact with the wall or brick-work of the furnace.

In Figures 5, 6 and 7 I have shown a modified form of construction of my invention, in which the charging port is angular 80 in cross section rather than oval, as shown in Figures 1, 2 and 3.

As indicated above, in this form of construction the top of the charging port is flat, and I provide an opening or passageway 9 through the frame-work from front to rear above the projection 7, the bottom of the passageway being substantially on the same horizontal plane as the top of the projection 7. This renders it practical to 90 make slight repairs to the furnace-wall 8 without removing the door-frame, by simply passing the brick through the opening 9 from the front of the frame, and placing them 95 in position in the wall.

I claim:

1. A furnace door-frame standing outside of the wall of the furnace, and having a charging-port provided at its inner end with a projecting flange or projection. 100

2. A furnace door-frame standing outside of the wall of the furnace, and having a charging-port provided at its inner end with a protecting flange or projection,—the inner wall of said flange being in alignment with 105 the outer wall of said charging-port.

3. A furnace door-frame standing outside of the wall of the furnace and having a charging-port provided at its inner end with an inwardly extending projection constitut- 110

ing an abutment or support for the adjacent wall of the furnace.

4. A furnace door-frame standing outside of the wall of the furnace and having a charging-port provided at its inner end with an inwardly extending projection constituting an abutment or support for the adjacent wall of the furnace,—the inner wall of said projection being in alignment with the outer wall of said charging-port.

5. A furnace door-frame of hollow construction standing outside of the wall of the furnace and having a charging-port provided at its inner end with a hollow protecting flange or projection communicating with the frame structure.

6. A furnace door-frame of hollow construction standing outside of the wall of the furnace and having a charging-port provided at its inner end with a hollow protecting flange or projection communicating with the frame structure,—the inner wall of said projection being in alignment with the outer wall of said charging-port.

7. A furnace door-frame of hollow construction standing outside of the wall of the furnace, and having a charging-port provided at its inner end with an inwardly extending hollow projection communicating with the frame structure, and constituting an abutment or support for the adjacent wall of the structure.

8. A furnace door-frame of hollow construction standing outside of the wall of the furnace, and having a charging-port provided at its inner end with an inwardly extending hollow projection communicating with the frame structure, and constituting an abutment or support for the adjacent wall of the furnace,—the inner wall of said projection being in alignment with the outer wall of said charging-port.

9. A furnace door-frame standing outside of the wall of the furnace, and having a charging-port provided at its inner end with

a protecting flange or projection, and an opening or passageway above the port.

10. A furnace door-frame of hollow construction standing outside of the wall of the furnace, and having a charging-port provided at its inner end with a protecting flange or projection,—the inner wall of said projection being in alignment with the outer wall of the charging-port, and also with an opening or passageway above the port. 55

11. A furnace door-frame standing outside of the wall of the furnace, and having a charging-port provided at its inner end with an inwardly extending projection constituting an abutment or support for the adjacent wall of the furnace, and also with an opening or passageway above the port.

12. A furnace door-frame of hollow construction standing outside of the wall of the furnace, and having a charging-port provided at its inner end with an inwardly extending hollow projection communicating with the frame structure, and constituting an abutment or support for the adjacent wall of the furnace, and also with an opening or 60 passageway above the port.

13. A furnace door-frame of hollow construction standing outside of the wall of the furnace, and having a charging-port provided at its inner end with an inwardly extending hollow projection communicating with the frame structure, and constituting an abutment or support for the adjacent wall of the furnace,—the inner wall of said projection being in alignment with the outer 70 wall of said port, and also with an opening or passageway above the port. 75

In testimony whereof I have hereunto affixed my signature in the presence of two witnesses.

JOHN THORNTON.
